US00D862096S

(12) **United States Design Patent** (10) Patent No.: **US D862,096 S**
(45) Date of Patent: ** Oct. 8, 2019

(54) **BENCH CAR SEAT**

(71) Applicant: **Nio Nextev Limited**, Hong Kong (HK)

(72) Inventors: **Kris Tomasson**, Hong Kong (HK);
Jochen Paesen, Hong Kong (HK);
Ryuichiro Goto, Hong Kong (HK);
Phil Gilman, Hong Kong (HK)

(73) Assignee: **NIO NEXTEV LIMITED**, Hong Kong (HK)

(**) Term: **15 Years**

(21) Appl. No.: **29/616,088**

(22) Filed: **Sep. 1, 2017**

(30) **Foreign Application Priority Data**

Apr. 10, 2017 (CN) 2017 3 0115146
Apr. 17, 2017 (CN) 2017 3 0127263

(51) **LOC (12) Cl.** **06-01**

(52) **U.S. Cl.**

USPC **D6/356**

(58) **Field of Classification Search**

USPC D6/334-336, 356, 367, 368, 374, 375,
D6/716, 716.1, 716.2, 716.3, 716.4, 716.5

Primary Examiner — Mimosa De

(74) Attorney, Agent, or Firm — Hogan Lovells US LLP

(57) **CLAIM**

The ornamental design for a bench car seat, as shown and described.

DESCRIPTION

FIG. 1 is a front view thereof;
FIG. 2 is a rear view thereof;
FIG. 3 is a right side view thereof;
FIG. 4 is a left side view thereof;
FIG. 5 is a top view thereof;
FIG. 6 is a bottom view thereof;
FIG. 7 is a perspective view thereof; and,
FIG. 8 is a perspective view thereof.

1 Claim, 8 Drawing Sheets
